CAN TESTER FEED MECHANISM

Ed Laxo, Oakland, Calif., assignor to Atlas Imperial Diesel Engine Co., Oakland, Calif., a corporation of Delaware

Application August 1, 1947, Serial No. 765,486

5 Claims. (Cl. 198—26)

1

The present invention relates to can testers, and more particularly to mechanisms for feeding cans onto the can carrier wheel of the tester.

In the gravity feed of cans into the pockets of the tester carrier wheel, the considerable weight of all cans in solid array in the inclined feed chute is relied upon to bear against the leading can and force it into a tester pocket at the proper time. The load on the leading can is so great as to tend to distort it, buckling the flanges and breaking open the side-seam. Moreover, reliance upon gravity for placing the cans successively into the pockets results in an uneven feed with a consequent tendency for the cans to be bent and damaged.

Accordingly, it is an object of the present invention to overcome the aforesaid disadvantages by providing a mechanism which feeds each leading can in the feed chute uniformly into a carrier wheel pocket.

Another object of the invention is to relieve the leading can in the feed chute of a can tester of the gravitational load of the following cans in the feed chute prior to the placing of the leading can in the tester carrier wheel pocket.

One form which the invention may assume is exemplified in the following description and illustrated by way of example in the accompanying drawings, in which:

Fig. 1 is a partial front elevation of a can tester.

Fig. 2 is a side elevation of part of the tester, parts being broken away to disclose internal features.

Fig. 3 is a fragmentary transverse section of the tester carrier wheel drive mechanism.

Fig. 4 is a fragmentary view of the apparatus for feeding successive foremost cans into successive pockets of the carrier wheel.

In the form of invention disclosed in the drawings, cans C are led from a can feed chute 10 for successive feeding or disposition into the circumferentially arranged pockets 11 of a carrier wheel 12 suitably mounted for rotation on the frame of the machine. As specifically illustrated, the frame includes a base portion 13 and spaced upright supports 14 to and between which a shaft 15 is secured, rotatably mounting the carrier wheel 12. Rotation of the wheel is effected in any suitable manner, as, for example, by transmitting the motion of a suitable electric motor 16 to a driving sprocket 17 which is encompassed by a chain 18 encircling the periphery of the carrier wheel 12, in order to effect a frictional drive of the carrier wheel at the proper rate of

speed. Radial pins 19 on the wheel may also effect a positive driving connection with the chain.

As the wheel 12 rotates, cans C are fed by gravity from the feed chute 10 into the successive pockets 11, being carried around the wheel for almost 360 degrees and then projected into a discharge chute 20. During its travel with the wheel between the feed and discharge chutes 10, 20, each can C is clamped in a pocket 11, compressed air is fed into the can, such air feed is cut off, and the can is thereafter communicated with a pressure responsive detecting mechanism 21 which determines the leakage condition, if any, in the can, and then automatically provides for its discharge into a good can portion or bad can portion of the discharge chute 20 following unclamping of the can from the carrier wheel 12 immediately after its connection with the detecting mechanism 21.

The general arrangement just described, in and of itself, forms no part of the present invention, and further details need not be given for a proper understanding of the instant invention. Such details, however, may be found in my copending applications for "Can Tester Drive Mechanism," Serial No. 765,488, filed August 1, 1947; "Can Tester Valve Mechanism," Serial No. 765,484, filed August 1, 1947 and now Patent No. 2,482,677, granted September 20, 1949; "Can Tester Leak Detecting Mechanism," Serial No. 765,485, filed August 1, 1947 and now Patent No. 2,551,020, granted May 1, 1951; and "Can Tester Pocket Assembly," Serial No. 765,483, filed August 1, 1947.

The can feed or intake chute 10 is ordinarily a continuation of a much longer chute leading from an overhead can conveyor and inclined downwardly to the tester at a rather steep pitch, leveling off at its point of connection to the feed chute at a substantially lesser pitch or incline. By virtue of the incline of the can feed chute arrangement, the cans C are fed by gravity toward the can pockets 11 on the carrier wheel.

The can feed chute 10 consists of opposed side members 22 having bottom channel-like flanges 23 whose groove 24 can receive the flanges of the can bodies C as they roll down the chute. The lower portions of the chute sides are mounted upon a supporting shaft 25 suitably secured to the side members 14 of the machine frame, the chute being held at a desired angle of inclination by supporting legs 26 fixed to a shaft 27 extending through the lower portions of the feed chute sides 22. The lower ends of the legs 26 are mounted upon a rod 28 secured to the side

members 14 just below the shaft 25 pivotally supporting the lower end of the chute on the machine frame.

The cans C are prevented from passing directly from the feed chute 10 into the pockets 11 of the carrier wheel 12. Instead the leading or foremost can is fed into the pocket without the gravitational load of the following cans being imposed thereon. To accomplish this purpose, a retarding and feeding device is provided, including a transverse shaft 29 rotatably mounted in a bracket 30 secured to a side frame 14 of the tester. A sprocket 31 is attached to one end of this shaft 29 and extends into the carrier wheel groove 32 so that its teeth engage the exterior of the chain 18 encompassing the carrier wheel, in order that the shaft 29 will be rotated by the chain during the rotation of the carrier wheel 12. A second sprocket 33 is secured to the shaft 29 on the other side of the bracket 30 and engages the exterior of a second chain 34 running around two spaced sprockets 35, 36, one of which 35 is rotatably mounted on a stud 37 suitably and adjustably secured to the frame of the machine, and the other of which 36 is secured to a shaft 38 extending between and rotatably mounted in spaced bell crank arms 39 pivotally mounted on the rod 28 passing through the lower ends of the chute supporting legs 26. These arms are adjustable about the rod by threaded rods 40 swivelly connected to the legs 26 and to other bell crank arms 41 extending outwardly of the rod 28.

A cam 42 is secured to the transverse shaft, and also a star wheel 43, the star wheel having arms 44 substantially in alignment with radial lobes 45 on the cam. In the specific form illustrated in the drawings, there are four cam lobes 45 disposed 90 degrees apart, and also four arms 44 on the star wheel 43 disposed 90 degrees apart.

The cam 42 is engageable with a cam follower roller 46 rotatably mounted on an adjusting plate 47 received within a pad or channel 48 formed intermediately along the length of a can retarding lever or arm 49 pivotally mounted upon a stud 50 fixed to one of the chute supporting legs 26. The adjusting plate 47 is movable within the pad 48 radially of the cam 42 and held in adjusted position by a bolt 51 extending through the lever 49 and a longitudinal slot 52 in the plate, the bolt 51 being tightened to clamp the plate 47 in any position of adjustment. The plate is adjusted inwardly when the mechanism is to feed larger cans from the feed chute 10 into the carrier wheel pockets 11, and is movable outwardly for the purpose of feeding smaller cans into the pockets. Such adjusting movement is required in order to appropriately position a retarding finger 53 adjustably bolted to the free, inner end of the arm 49 and extending inwardly across the outlet end of the feed chute 10. It will be apparent that as the cam 42 rotates, the lever 49 is caused to move outwardly on its pivot 50, and it must move outwardly to a greater extent to permit large cans to pass from the chute 10 into the pockets than small cans. Conversely, when smaller cans are being fed into the tester, the extent of movement of the retarding finger 53 must be closer to the bottom of the feed chute 10, in order to act as a stop device for the cans C and yet move upwardly to permit the cans to pass beyond the retarding finger.

The adjusting studs 40 are also turned in the proper direction to move the shaft 38 and axis of the cam 42 and star wheel 43 downwardly from

the chute to feed large cans C into the wheel 12, and in the opposite direction to operate effectively upon smaller cans.

While the cam 42 moves the lever 49 and its retarding finger 53 upwardly to permit cans C to pass out of the feed chute 10, a spring 54, having one end attached to the chute supporting leg 26 and its other end to a lug 55 secured to the rear of the lever 49, urges the lever toward the cam 42 to maintain its follower roller 46 in engagement with the cam lobes 45 and to urge the retarding finger 53 downwardly toward the bottom of the feed chute. The extent of inward movement of the lever 49 is limited by engagement of a screw 56 threaded through a boss 57 on the lever with a stationary member, such as the shaft 25 supporting the feed chute 10. This screw 56 can be held in various positions of adjustment by clamping a lock nut 58 threaded thereon against the boss 57. The star wheel 43 is fixed on the shaft 38 and extends upwardly into the feed chute 10 between its sides 22 so as to arrest the cans C in their downward travel through the feed chute.

The cam 42 and star wheel 43 are rotated in accordance with the rotation of the carrier wheel 12. In the specific construction illustrated, the cam and star wheel rotate 90 degrees as the carrier wheel moves the angular distance between adjacent pockets 11. The cans C are fed by gravity down the feed chute 10 and are arrested by engagement of the leading can with the back face 44a of one of the star wheel arms 44. As the carrier wheel 12, cam 42 and star wheel 43 continue their rotation, the cam follower roller 46 rides down a cam lobe 45 toward an adjacent low point on the cam, which allows the spring 54 to shift the retarding finger 53 downwardly, this finger then sustaining the entire load of the cans in the chute 10 and preventing the cans from moving against the carrier wheel 12. As rotation continues, the leading can is cradled in the star wheel between its arms 43 and is fed toward a pocket 11 on the carrier wheel, the next succeeding cam lobe 45 then engaging the follower 46 to elevate the retarding finger 53 from the path of the cradled can. Despite the elevation of such retarding finger, the rear 44a of the trailing cradling arm holds back the following cans in the chute 10, and the star wheel 43 feeds the leading can into a pocket 11 without such leading can being subject to the gravitational force of the bank of cans in the feed chute. The aforesigned cycle of operation is repeated for each can, which is successively cradled in the star wheel 43, relieved from the load of the following cans, and then fed smoothly into a carrier wheel pocket 11.

It is, accordingly, apparent that by virtue of the invention the foremost can body is not subject to the force or pressure of the can bodies in the feed chute. As a consequence, cans can be fed or rolled into the tester pockets gently and without distortion, thus eliminating bent flanges, broken laps or crushing of the cans. Moreover, the following cans are caused to progress in a uniform manner toward the star wheel, which then feeds them in exact timed relation with the positioning of the pockets on the carrier wheel adjacent the foremost cans. Such uniform and equally timed movements minimize the danger of deforming and damaging the cans.

While I have shown the preferred form of my invention, it is to be understood that various changes may be made in their construction by those skilled in the art without departing from

the spirit of the invention as defined in the appended claims.

Having thus described my invention, what I claim and desire to secure by Letters Patent is:

1. A feeding device of the character described adapted to feed can bodies to a can body testing wheel, comprising an inclined feed chute having a lower end and defining a path of travel for can bodies; a rotary feed member having radial arms and disposed inwardly of said lower end and such that each of said arms, in succession, lies athwart said path of travel whereby the bottommost can body in said chute is cradled in a pair of arms and is fed forwardly and positively thereby while the rearward of said pair of arms obstructs the next can body; a gate at the lower end of said chute operable to prevent egress of a can body from said feed member and chute by gravity; and means operable to rotate said feed member and to open said gate in timed relation to said feed member.

2. A feeding device of the character described adapted to feed can bodies to a can body testing wheel, comprising an inclined feed chute having a lower end and defining a path of travel for can bodies, a rotary feed member having radial arms and disposed inwardly of said lower end and such that each of said arms, in succession, lies athwart said path of travel whereby the bottommost can body in said chute is cradled in a pair of arms and is fed forwardly and positively thereby while the rearward of said pair of arms obstructs the next can body, a gate at the lower end of said chute operable to prevent egress of a can body from said feed member and chute by gravity, means operable to rotate said feed member and to open said gate in timed relation to said feed member, and means for adjusting the position of said rotary feed member relatively to said chute to accommodate cans of different diameters.

3. A feeding device of the character described adapted to feed can bodies to a can body testing wheel, comprising an inclined feed chute having a lower end and defining a path of travel for can bodies, a rotary feed member having radial arms and disposed inwardly of said lower end and such that each of said arms, in succession, lies athwart said path of travel whereby the bottommost can body in said chute is cradled in a pair of arms and is fed forwardly and positively thereby while the rearward of said pair of arms obstructs the next can body, a gate at the lower end of said chute operable to prevent egress of a can body from said feed member and chute by gravity, means operable to rotate said feed member and to open said gate in timed relation to said feed member, and means for adjusting the degree of opening of said gate to accommodate can bodies of different diameters.

4. A feeding device of the character described adapted to feed can bodies to a can body testing

machine comprising an inclined chute having a lower end and defining a path of travel for can bodies, a rotary feed member having radial arms and disposed inwardly of said lower end and such that each of said arms, in succession, lies athwart of said path of travel whereby the bottommost can body in said chute is cradled in a pair of arms and is fed forwardly and positively thereby while the rearward of said pair of arms obstructs the next can body, a shaft on which the rotary feed member is mounted, means adjustably supporting the shaft for movement toward and away from the chute, a cam on the shaft, a gate at the lower end of said chute operable to prevent egress of a can body from said feed member and chute by gravity, an arm carrying the gate at one end thereof and pivoted adjacent the other end thereof, a follower carried by the arm intermediate the pivot point and the gate and engaging the cam so as to cause said gate to open in timed relation to said feed member, and means for rotating said shaft.

5. A feeding device of the character described adapted to feed can bodies to a can body testing machine comprising an inclined chute having a lower end and defining a path of travel for can bodies, a rotary feed member having radial arms and disposed inwardly of said lower end and such that each of said arms, in succession, lies athwart said path of travel whereby the bottommost can body in said chute is cradled in a pair of arms and is fed forwardly and positively thereby while the rearward of said pair of arms obstructs the next can body, a shaft on which the rotary feed member is mounted, means adjustably supporting the shaft for movement toward and away from the chute, a cam on the shaft, a gate at the lower end of said chute operable to prevent egress of a can body from said feed member and chute by gravity, an arm carrying the gate at one end thereof and pivoted adjacent the other end thereof, a follower carried by the arm intermediate the pivot point and the gate and engaging the cam so as to cause said gate to open in timed relation to said feed member and means for rotating said shaft in its adjusted position.
